W. A. SMITH

STEEL RETAINER

Filed Aug. 6, 1923

INVENTOR
William A. Smith.

By
Robert H. Odde
HIS ATTORNEY

UNITED STATES PATENT OFFICE.

WILLIAM A. SMITH, OF ATHENS, PENNSYLVANIA, ASSIGNOR TO INGERSOLL-RAND COMPANY, OF JERSEY CITY, NEW JERSEY, A CORPORATION OF NEW JERSEY.

STEEL RETAINER.

Application filed August 6, 1923. Serial No. 655,920.

To all whom it may concern:

Be it known that I, WILLIAM A. SMITH, a citizen of the United States, and a resident of Athens, county of Bradford, and 5 State of Pennsylvania, have invented a certain Steel Retainer, of which the following is a specification, accompanied by drawings.

This invention relates to drill steel retainers of the type in which a yoke 10 braces the steel and is suitably held in position upon the front head of the tool.

The primary object of the present invention is to produce a yoke retainer having portions which are adapted to frictionally 15 engage a front head member for holding the retainer in a desired operative or inoperative position, relative to the drill steel.

Another object of the invention is to secure a retainer which is simple in its construction and operation, cheap to manufacture and readily applied to the front head 20 of a rock drill or a similar machine.

Further objects will hereinafter appear and the invention is shown in the accompanying drawings, in which

Figure 1 is a side elevation of the front end of a rock drill,

Figure 2 is a side elevation at right angles to Figure 1,

30 Figure 3 is a horizontal sectional view taken on the line 3-3 of Figure 2 looking in the direction of the arrows, and

Figure 4 is a vertical sectional view of the front end portion of the rock drill taken 35 on the line 4-4 of Figure 3.

Referring to the drawings, A represents a portion of a front head of a fluid actuated percussive tool, in this instance a rock drill. The front head is adapted to be held 40 to the usual cylinder by the spring pressed side bolts B. A portion of a reciprocating hammer piston C, and a rotation sleeve D are indicated for the purposes of illustration. The sleeve D is adapted to receive and 45 impart rotation to the collared steel E. The piston and sleeve form no part of the present invention and further description thereof is deemed unnecessary.

In accordance with the present invention, 50 the front head A is formed with a reduced and preferably tapered end portion F and a ring G abuts against a shoulder H on the front head. The ring G preferably carries diametrically opposed trunnions J on 55 which the side arms K of the steel retainer

are pivoted. A yoke L is in this instance formed integrally with the side arms K and is adapted to embrace the drill steel E below the collar E'. In order to cushion the outward movement of the yoke L, a coil 60 spring O is mounted on the tapered end portion F of the front head between the ring G and the flange F' on the extreme forward end of the tapered portion F. A portion of a screw thread P is formed in 65 the flange F' to permit the coil spring O to be readily twisted onto the front head by turning the spring on the screw thread.

In order to hold the yoke L and arms K in operative position relative to the drill 70 steel E, portions of the arms K are bent inwardly at Q, and these bent-in portions extend under and frictionally engage the underside of the ring G, so that the yoke L is held in position about the drill steel E. 75 Whenever it is desired to remove the drill steel from the front head, the yoke L and side arms K may be swung on their pivots away from the steel and the bent end portions Q will frictionally engage the ring G 80 thereby holding the retainer in the desired inoperative position. The arms K may be swung to such an extent that the bent portions Q engage the top of the ring G and thus hold the yoke L away from the drill 85 steel.

This drill steel retainer is extremely simple in its construction, the cost of manufacture comparatively small and the retainer operates satisfactorily and efficiently. 90

I claim:

1. A drill steel retainer comprising in combination with a front head, a ring encircling the front head longitudinally movable, cushioned trunnions on said ring, a yoke adapted to embrace a drill steel, side arms carried by the yoke and pivoted to said trunnions, inwardly bent end portions on said arms adapted to frictionally retain the yoke in operative position about the 100 drill steel or in inoperative position away from the drill steel.

2. A drill steel retainer comprising in combination with a front head, a ring encircling the front head, trunnions carried by the ring, means for cushioning the movement of the ring, a yoke adapted to embrace a drill steel, side arms carried by the yoke and pivoted on said trunnions, the end portions of said side arms being bent to frictionally retain 110

the yoke in operative position about the drill steel or in inoperative position away from the drill steel.

3. A drill steel retainer comprising in combination with a front head, a ring encircling the front head, trunnions carried by the ring, a coiled spring for cushioning the movement of the ring in one direction, a yoke adapted to embrace a drill steel, side 10 arms carried by the yoke and pivoted to said trunnions, inwardly bent end portions on said side arms adapted to cooperate with said ring for holding the side arms in operative position about the drill steel or in 15 inoperative position away from the drill steel.

4. A drill steel retainer comprising in combination with a front head having a reduced end portion, a ring encircling the front head, trunnions carried by the ring, 20 a coil spring encircling the reduced portion of the front head, a yoke adapted to embrace a drill steel, side arms integral with the yoke and pivoted to said trunnions, inwardly bent end portions on said arms 25 adapted to cooperate with said ring for holding the said arms in a desired operative position about the drill steel or in inoperative position away from the drill steel.

In testimony whereof I have signed this 20 specification.

WILLIAM A SMITH.
